US00D628994S

(12) **United States Design Patent**
Griffin, Jr. et al.

(10) **Patent No.:** US D628,994 S
(45) **Date of Patent:** ** Dec. 14, 2010

(54) **CASE FOR MOBILE PHONE**

(75) Inventors: **Paul P. Griffin, Jr.**, Nashville, TN (US);
Steven P Greenwell, Nashville, TN (US)

(73) Assignee: **Griffin Technology, Inc.**, Nashville, TN (US)

(**) Term: **14 Years**

(21) Appl. No.: **29/318,931**

(22) Filed: **May 30, 2008**

(51) LOC (9) Cl. **14-03**

(52) U.S. Cl. **D14/250**

(58) **Field of Classification Search** D14/140,

(57) **CLAIM**

The ornamental design for a case for a mobile phone, as shown and described.

DESCRIPTION

FIG. 1 is an isometric view showing the new design for a case for a mobile phone;

FIG. 2 is an exploded view of the case for a mobile phone;

FIG. 3 is a front view of the case for a mobile phone;

FIG. 4 is a back view of the case for a mobile phone;

FIG. 5 is a left side view of the case for a mobile phone;

FIG. 6 is a right side view of the case for a mobile phone;

FIG. 7 is a top view of the case for a mobile phone; and,

FIG. 8 is a bottom view of the case for a mobile phone.

The broken lines in the drawing figures are for the purpose of illustrating a mobile phone that forms no part of the claimed design.

1 Claim, 8 Drawing Sheets
